Primary Examiner — Dana Meyrow(74) Attorney, Agent, or Firm — Ronald T. Sia; Kevin C. Johnson(57) CLAIM

The ornamental design for a shave preparation container, as shown and described.

DESCRIPTION

FIG. 1 is a perspective view of a shave preparation container showing my new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The broken lines in the drawings illustrate the portions of the shave preparation container that form no part of the claim.
